UNITED STATES PATENT OFFICE.

ELMORE FRANKLIN SHUSTER, OF NEW HAVEN, CONNECTICUT.

WIRE STRAIGHTENING AND CUTTING-OFF MACHINE.

1,126,892.

Specification of Letters Patent.

Patented Feb. 2, 1915.

Application filed May 21, 1914. Serial No. 839,827.

To all whom it may concern:

Be it known that I, ELMORE FRANKLIN SHUSTER, citizen of the United States, residing at New Haven, in the county of New Haven and State of Connecticut, have invented certain new and useful Improvements in Wire Straightening and Cutting-Off Machines; and I do hereby declare the following to be a full, clear, and exact description of the invention, such as will enable others skilled in the art to which it appertains to make and use the same.

My invention relates to wire straightening and cutting off machines, and it consists of an arrangement of mechanism for driving all of the rotatable parts of the machine by means of a single belt drive directly from the straightening arbor.

The object of my invention is to eliminate a plurality of the countershafts, pulleys and gears heretofore employed on machines of this character, besides enabling the machine head to be greatly reduced in width and a corresponding reduction in the cost of construction.

Referring to the drawings wherein the same figures of reference indicate like parts throughout the several views: Figure 1 represents a side elevation of the machine head, broken view of the base, rock shaft and guide bar; and Fig. 2 is an end view looking in the direction of arrow *a* of Fig. 1.

The straightening arbor 1, journaled in the projections 2 of the head 3, carries the worm 4 meshing with the large gear 5 secured to the transversely located driving shaft 6 journaled in the machine head 3 and the bracket 7 integral with the head.

8 is a large spur gear mounted on the projecting end of the driving shaft and it meshes with the gear 9 on the projecting end of the lower feed roll shaft 10, and also with the large gear 11 on the cam shaft 12. The upper feed roll shaft 13 is rotated as usual from the lower feed roll shaft through the medium of the pinions 14, 15. These shafts carry the usual feed rolls 16, 17.

The large gear 11 on the cam shaft 12 serves the same purpose as the usual balance wheel pulley and runs idle during the time the proper length of wire is being fed forward by the feed rolls. The movement of

the cutting off lever 18, mounted on the rock shaft 19 and carrying the usual guide bar 20, is accomplished in the usual manner by means of the key 21, clutch lever 22, cam 23, roll 24 mounted on the pin 25 secured to the lower end of the cutting off lever. The wire 26 on the end of the clutch lever connects with the usual mechanism (not shown) for tripping said lever and setting the cutting off mechanism in operation when the predetermined length of wire has been fed forward. The usual manual tripping mechanism comprises the rod 27, lever 28 and handle lever 29 attached to said rod.

30 is a pulley integral with the straightening arbor 1, and said arbor is rotated by a belt (not shown) adapted to connect said pulley with overhead driving mechanism 70 (not shown). This belt is the only one used in connection with the machine. All of the gears, as before mentioned, are rotated directly from the straightening arbor, thus avoiding the use of a plurality of belts and giving a more uniform and positive drive. The gears are so constructed as to their diameters and the proper working speed developed so that the gear on the cam shaft can be made large enough to serve the purpose of a balance wheel, thus avoiding the expense of mounting an extra balance on said shaft and belt to drive the same.

Having thus described my invention, what I claim is:—

In a machine of the character described having a head, a straightening arbor rotatably mounted therein, feed rolls, and a cam shaft for actuating a cutting off lever, a worm mounted on the straightening arbor, 90 a driving shaft journaled transversely in the head, a worm gear on one end of said shaft meshing with said worm, a train of gears connecting the driving shaft, one of the feed roll shafts and cam shaft, the gear on said cam shaft adapted to run free during the wire feeding operation, and means for connecting said gear with the cam shaft.

In testimony whereof I affix my signature in presence of two witnesses.

ELMORE FRANKLIN SHUSTER.
